DRAWING BOARD EASEL

Sven A. Vaule and Rae D. Vaule, Freeport, Ill.

Application December 22, 1945, Serial No. 636,556

7 Claims. (Cl. 35—60)

1

This invention relates to a new and improved drawing board easel especially designed and adapted for use in the home and schoolroom, and having the drawing boards on opposite sides of the easel adjustable quickly and easily up and down to suit users of various heights.

The easel of our invention also embodies the following features:

1. The clamping bolts projecting from the drawing boards and adjustable up and down in slots in the legs of the easel have large, flat, thin heads which fit in recesses in strips applied to the backs of the drawing boards, thus, obviating the necessity for having any holes in the drawing board proper or having any exposed fastening screws or the like, inasmuch as the strips may be glued to the back of the drawing boards, this construction, incidentally, adding strength and stiffness to the boards.

2. There is a paint and crayon trough on the bottom portion of each drawing board which is adjustable with the board and also tends to add rigidity.

3. A paper container is hinged at one end to one section of the easel between the legs thereof and is arranged to rest on a ledge provided on the other section of the easel when the easel is unfolded for use, thus making the drawing material in the container easily accessible for use while at the same time enabling the storage of the drawing material inside the easel when the easel is folded, the container being foldable upwardly between the legs of the one section and having a suitable catch to lock the same releasably in the folded position.

4. The paper container has a horizontally projecting flange on the top thereof at the hinged end so as to form a pocket to retain drawings and drawing material left in the container when the same is folded up between the legs of the easel.

The invention is illustrated in the accompanying drawings, in which—

Figure 1 is a side view of a drawing board easel made in accordance with our invention, the one paint and crayon trough and the paper-container and adjacent portions of the easel being shown in section for purposes of better illustration;

Figs. 2 and 3 are perspective views of the easel in unfolded and folded conditions, these two views showing the two drawing boards adjusted to

2

different elevations to suit two children of different sizes;

Fig. 4 is a front view of Fig. 1, and

Fig. 5 is a sectional detail on the line 5—5 Fig. 4.

The same reference numerals are applied to corresponding parts through the views.

The easel indicated generally by the reference numeral 6 comprises sections 7 and 8 hingedly connected at the top as indicated at 9 to unfold to the condition shown in Figs. 1 and 2 for use and fold to the condition shown in Fig. 3 for storage. Section 8 of the easel has its legs 10 and 11 connected by the cross-pieces 12 and 13,

whereas the legs 14 and 15 of section 7 are connected by only one cross-piece 16, the hinges 9 at the upper ends of these legs connecting the same to the upper ends of the legs 10 and 11 of the other section being sufficient along with the

cross-piece 16 to give rigidity to section 7. Two drawings boards 17 and 18 are mounted on opposite sides of the easel and have bolts 19 projecting therefrom and entered in slots 20 provided in the legs 10—11 and 14—15 of the easel. The drawing

boards are preferably made of plywood as indicated in section in Fig. 5 and are preferably reinforced by applying plywood strips 21 to the back along the opposite side portions, another plywood strip 22 being preferably applied to the back across the top portion. These strips 21 and 22 are preferably glued to the drawing boards so that no fastening screws or the like will be exposed on the working surface. The bolts 19, for a similar reason, are of a type having broad, flat heads 23

which are countersunk in recesses provided therefor in the strips 21, for good anchorage and rigidity of the bolts. If preferred, the recesses 23 may be provided in the backs of the boards 17 and 18, or partly in the strips 21 and partly in the boards. The bolts receive wing nuts 24 or other nuts and washers 25 on their projecting ends, and when these nuts are tightened, the drawing boards are held firmly in adjusted positions and the entire easel is found to be quite

sturdy and rigid and capable of withstanding the rough usage it is apt to get from youngsters. The two drawing boards 17 and 18 may, of course, be adjusted independently of one another and one may be set low and the other high as illustrated,

for example, in Fig. 2 to suit smaller and larger

children and adults. The fact that two children are accommodated at one time is, of course, a big advantage not only from the standpoint of economy in cost, but economy in space in the home and schoolroom. It also eliminates likelihood of children quarreling over the use of a single board and tends to promote desirable competition along educational lines.

Each of the drawing boards has a paint and crayon trough 26 built onto the lower portion thereof for storage of paints and crayons, the board itself forming the back wall of the trough as indicated at 27 so that only the bottom, front and two ends are required to complete the same. A cross-piece 28 is glued or otherwise suitably secured to the front of the board in the upper rear portion of the trough and has a suitable recess 29 provided therein to accommodate paint brushes and crayons. There is also preferably a partition 30 in each trough at an intermediate point. With this construction, it is obvious that the troughs adjust up and down with the drawing boards, which, of course, is highly desirable, and the troughs lend strength and rigidity to the drawing boards and take the place of an additional cross-piece that might otherwise be required on the back of each drawing board on the lower portion for stiffness and strength.

The paper container 31 is in the form of a sheet metal tray of rectangular form narrow enough to fit between the legs 10-11 and 14-15, as clearly indicated in dotted lines in Fig. 4, so that the container may be folded from its horizontal operative position shown in Figs. 1 and 2 up into a vertical position between the legs of the easel when the easel is folded as shown in Fig. 3. The container 31 is for paper and other drawing materials and is hinged at one end as indicated at 32 to the upper inner portion of the cross-piece 13 so that in folding, it will move to a position over the cross-piece 13 and between the legs 10 and 11. The cross-piece 12 is located far enough above the cross-piece 13 to afford clearance there-beneath for the container in its folded position and there is a spring pressed bullet type catch 33 on the cross-piece 12 which engages behind a keeper 34 on the free end of the container to lock the container releasably but securely in its folded position. The catch yields easily enough so that the container can be unfolded for use by a pull on the handle 39 that is pivoted at 40 to fold flat against the bottom of the container. That portion of the container which projects from the section 8 of the easel in the folded position of the container will be accommodated between the legs 14 and 15 of section 7 so that there is nothing to interfere with the folding of the easel to a compact size. The transverse flange or lip 35 across the top of the hinged end of the container is a very handy addition to the container because it forms a pocket in the lower end of the container to retain the drawings and drawing materials when the container is folded up. A pair of ledges 36 are provided on the cross-piece 16 for support of the free end of the container 31 in its unfolded operative position, and one or two chains 37 connected at their opposite ends to the sections 7 and 8 of the easel serve to limit the spreading apart of these sections when the easel is unfolded for use, thereby eliminating likelihood of the free end of the container 31 slipping off the ledges 36 and spilling the contents.

It should be evident from the foregoing description that we have provided a drawing board easel

having many advantages and highly desirable features and yet the construction is relatively simple and inexpensive.

It is believed the foregoing description conveys a good understanding of the objects and advantages of our invention. The appended claims have been drawn to cover all legitimate modifications and adaptations.

We claim:

10. 1. An easel comprising two frame sections of skeleton construction hingedly connected at the top to be foldable together for storage and unfoldable to spread apart relationship for use, a drawing board mounted on the outer face of each 15 of said frame sections leaving storage spaces behind the same within the frame sections, and a tray-like container for paper and drawing materials hingedly connected at one end to one of said frame sections and foldable from an operative 20 position disposed horizontally between and supported at opposite ends upon the spread apart frame sections to a raised inoperative position disposed between and substantially parallel to the drawing boards and housed in the storage 25 spaces in the frame sections in their folded together relationship.
2. An easel comprising two frame sections of skeleton construction hingedly connected at the top to be foldable together for storage and unfoldable to spread apart relationship for use, a drawing board mounted on the outer face of each 30 of said frame sections leaving storage spaces behind the same within the frame sections, a tray-like container for paper and drawing materials hingedly connected at one end to one of said 35 frame sections and foldable from an operative position disposed horizontally between and supported at opposite ends upon the spread apart frame to a raised inoperative position disposed 40 between and substantially parallel to the drawing boards and housed in the storage spaces in the frame sections in their folded together relationship, and catch means on the same frame section onto which the container is hinged for releasably 45 locking said container to said frame section in the raised inoperative position of said container.
3. An easel comprising two frame sections hingedly connected at the top to be foldable together for storage and unfoldable to spread apart 50 relationship for use, one of said sections having vertically extending, substantially parallel, elongated slots in the opposite side portions thereof, and a drawing board mounted on said easel section having clamping bolts projecting from the 55 back thereof on the opposite side portions thereof and movable vertically in said slots for up and down adjustment of said board, and having nuts threaded on said bolts tightenable against the slotted frame section to hold the drawing board 60 in selected positions of adjustment.
4. An easel comprising two frame sections hingedly connected at the top to be foldable together for storage and unfoldable to spread apart 65 relationship for use, one of said sections having vertically extending, substantially parallel, elongated slots in the opposite side portions thereof, a drawing board mounted on said easel section having clamping bolts projecting from the back thereof on the opposite side portions thereof 70 and movable vertically in said slots for up and down adjustment of said board, and having nuts threaded on said bolts tightenable against the slotted frame section to hold the drawing board in selected positions of adjustment, and a trough 75 for paints and crayons provided on the lower

portion of said drawing board as an integral portion thereof for adjustment up and down with said board.

5. As an article of manufacture, a substantially rectangular drawing board adapted to be mounted on an easel in an upright position, a trough for paints and crayons of box-like form built onto the lower portion of said drawing board and utilizing said lower portion as the back wall of the trough, said trough reinforcing the lower portion of said drawing board and eliminating need for other reinforcing in this portion, and there being reinforcing members applied to the back of said drawing board extending vertically along opposite side edge portions and across the upper edge portion, and flat headed bolts for fastening said drawing board to an easel, said bolts extending from the back of said drawing board through holes in said reinforcing members, the heads of said bolts being received in recesses provided therefor between said drawing board and reinforcing members.

6. An easel comprising two frame sections hingedly connected at the top to be foldable together for storage and unfoldable to spread apart relationship for use, one of said sections having vertically extending, substantially parallel, elongated slots in the opposite side portions thereof, and a thin drawing board panel mounted on said easel section, reinforcing strips applied to the back of said panel, and flat headed bolts entered in said slots for fastening said drawing board panel to said easel section, said bolts extending from the back of said drawing board panel through holes in said strips and having the heads thereof received in recesses provided therefor between said drawing board panel and strips, said bolts having nuts threaded thereon tightenable against the slotted easel section to hold the drawing board in selected positions of adjustment.

7. An easel comprising two frame sections

hingedly connected at the top to be foldable together for storage and unfoldable to spread apart relationship for use, one of said sections having vertically extending, substantially parallel, elongated slots in the opposite side portions thereof, and a substantially rectangular drawing board adapted to be mounted on said easel section in an upright position, a trough for paints and crayons of box-like form built onto the lower portion of said drawing board and utilizing said lower portion as the back wall of the trough, said trough reinforcing the lower portion of said drawing board and eliminating need for other reinforcing in this portion, and there being reinforcing members applied to the back of said drawing board extending vertically along opposite side edge portions and across the upper edge portion, and flat headed bolts for fastening said drawing board to said easel, said bolts extending from the back of said drawing board through holes in said reinforcing members, the heads of said bolts being received in recesses provided therefor between said drawing board and reinforcing members, said bolts having nuts threaded thereon tightenable against the slotted easel section to hold the drawing board in selected positions of adjustment.
